DISPENSER WITH FLOW RESTRICTING
VALVE

Robert Gordon Bau, North Hollywood, Calif.

Application July 19, 1947, Serial No. 762,079

3 Claims. (Cl. 222—95)

1

The invention relates to a dispenser for face cream or similar cosmetic or viscous material wherein a casing is provided with a removable cartridge having a flexible bag, a spring pressed plunger being provided to exert pressure on the bag, and the casing having a valve operator to control the discharge of the bag contents.

An object of the invention is to simplify and improve the construction of the dispenser disclosed and claimed in the following cases which disclose and claim several features disclosed herein.

The design is covered by Design Patent No. 140,111, patented January 23, 1945, for Dispenser for cosmetic creams. The valve control of a spring loaded removable cartridge is covered by application S. N. 555,451, filed September 25, 1944, for Dispenser. The double valve for controlling the outlet is covered by application S. N. 594,672, filed May 19, 1945, for Dispenser. A cartridge having a seal between the open end of a flexible bag and a cup-shaped top, also a check valve control for the bag therefor are covered by application S. N. 629,585, filed November 19, 1945, for Dispenser.

More particularly, an object of the invention is to improve the manner of subjecting the bag to or removing it from the action of the spring pressed plunger, the action of the spring pressed plunger on the bag being automatically removed when the casing is taken apart for the purpose of removing an empty cartridge to be replaced by a full cartridge, the fresh cartridge being insertible into the casing free from pressure by the spring pressed plunger, and the spring pressed plunger being automatically brought into play against the flexible bag in the course of securing the top of the casing on the bottom of the casing. In the example shown, the casing parts are held together by a screw thread and the operations previously described are accomplished without relative rotation between the spring pressed plunger and the bag while the casing parts are being coupled or uncoupled.

The above object is accomplished by automatically retracting the spring pressed plunger into the bottom of the casing away from the flexible bag while the casing top is being unscrewed, whereby there is no pressure of the spring pressed plunger on the bag at the time that a fresh cartridge is inserted in the casing, the plunger being advanced towards and fully acting on the bag in the course of fastening the casing top in place. According to another feature of the invention, relative rotation between the flexible bag and spring pressed plunger is prevented during the time that the casing parts are relatively rotated to secure them together or take them apart, by causing the plunger and the bag to rotate as a unit during that time.

2

According to a further feature of the invention, an improved check valve is provided for the neck of the cartridge, with an improved valve operator which preferably embodies also an additional metering valve, the metering valve and the valve operator on the casing being brought into operative relation with the check valve on the cartridge when the cartridge is assembled in the casing. According to this feature, the neck of the cartridge provides a seat for the metering valve and when the operator is actuated, the metering valve is moved toward closed position as the check valve is moved toward open position to graduate the flow and finally reduce the flow to zero, which not only controls the flow of fluid material but also stops it in the extreme position of the valve operator to prevent an undue amount of fluid from being expelled.

For further details of the invention, reference may be made to the drawings wherein

Fig. 1 is a front view in elevation of a dispenser according to the present invention.

Fig. 2 is an enlarged vertical sectional view on line 2—2 of Fig. 1, looking in the direction of the arrows, the cartridge being illustrated as full of face cream or the like, the valve operator being in elevated position.

Fig. 3 is an enlarged partial sectional view with parts broken away, showing the check valve in open position, the valve being in actuated position.

Fig. 4 is a sectional view corresponding to Fig. 2 with the bag empty.

Fig. 5 is a perspective view of the cartridge and its flexible bag.

Fig. 6 is a perspective view of a rotatable cage shown in the preceding figures for spring pressed plunger.

Fig. 7 is a sectional view on line 7—7 of Fig. 4, looking in the direction of the arrows.

Fig. 8 is an exploded perspective view of a portion of the valve operator and the top of the casing.

Fig. 9 is a perspective view of the check valve support for the cartridge.

Referring in detail to the drawings, the dispenser 1 comprises a casing having a top 2 and a bottom 3 secured together by elongated screw threads 4. The fluid contents are expelled through an outlet 89 in the casing top, under control of a reciprocating valve operator 5. The casing 2, 3 may be made of plastic or other suitable material, and have shapes suitable for casting or molding.

The fluid contents such as face cream are contained in a cartridge 6 shown in Fig. 5. The cartridge 6 has a ridge cup-shaped top 7 which rotatably fits in the corresponding cup-shaped concave bore 8 in the casing top 2. The cartridge top 7 has an annular shoulder 9 which fits a

corresponding shoulder 10 in the bore 8. Arising from the shoulder 9 is a conical neck 11 which fits in the conical bore 12 in the top 2. The conical portion 11 terminates in a flat annular surface 13, the outer portion of which rests against a gasket 14 around the cylindrical bore 15 in the casing top 2. Extending across the inside of neck 11 is a spider in the form of a disk 16 of plastic seated in and cemented to an annular groove 17 at the inner portion of neck 11. The spider 16 is also shown in Fig. 9, and it has a series of ports indicated at 18 to permit the fluid contents of the cartridge 6 to issue. Arising from the center of spider 16 is a post 19 which serves as a guide for the hollow stem 20 on a check valve 21. Valve 21 opens inwardly of the cartridge 6 and it has a seat 22 facing inwardly of the cartridge and arranged on the inner side of the end of neck 11. The seat 22 surrounds a port 23 through which the fluid issues.

Secured to the bottom of the cartridge top 7 is the open end 26 of a flexible bag 25. The end 26 of the bag terminates as indicated at 27 in Fig. 2, between two telescoping parts, namely, the outer end 28 of the cartridge top 7, and a ring 29 having external screw threads 30. The ring 30 is of plastic and cemented to the plastic top 7 to form a joint which extends beyond the end 26 of the bag as indicated at 95, to prevent leakage past the end of the bag.

The bag 25 has substantially the same capacity as the cup-shaped top 7. When the bag 25 is full as shown in Fig. 2, the capacity of the cartridge 6 is equal to the sum of the capacities of the bag 25 and the top 7, the bag at this time as shown in Fig. 2, extending outwardly from the joint between the open end 26 of the bag and the parts 28 and 29. When the bag 25 is empty as shown in Fig. 4, its side 90 fits the concave side 91 of top 7 and its flat bottom 32 fits against the inner surface of the spider 16, being held or fitted against it by a spring pressed plunger 31 which has a convex contour fitting the convex contour of the cartridge top 7, and a flat bottom 79. At this time, with bag 25 empty as shown in Fig. 4, the bottom 32 of the bag extends across and is sandwiched between the inner side of spider 16 and plunger bottom 79 to expel all the bag contents.

The outer surface of spider 16 has an annular ridge 33 to support the end of a spring 34 coiled in the shape of a cone and its outer and smaller end engages a recess 35 in the valve 21 to urge it to closed position.

Assuming for the moment that the cartridge 6 is in the casing 2, 3 as shown in Figs. 2 and 3, the flow of fluid from the cartridge is controlled as follows. As shown in Fig. 8, the outer end of the casing top 2 has an annular recess 36 in which is a cylindrical bearing 37 having a bore 38 to slidably support the stem 39 of the valve operator 5. The stem 39 has a cylindrical portion 40 which slidably fits in the bore 36 and it has an inner cylindrical sleeve 41 inside of which are two oppositely disposed longitudinally extending ribs 42, 43. If the operator 5 is turned so that the ribs 42, 43 match with the short recesses 44, 45 on the bearing 37, the operator 5 cannot be pushed in to operate the check valve 21. If the operator 5 is rotated a quarter turn in either direction, the ribs 42, 43 will slide in the extended grooves 46, 47 in the surface of the bearing 37, to operate valve 21.

In assembling the operator 5 on the top 2, 75

the stem 39 is inserted in the bore 38 and then as shown in Fig. 4, the cylindrical cup-shaped valve 48 is mounted on the reduced end 49 of the stem 39, a leaf spring 50 is mounted on stem 49 against the underside of the cup and a disk retainer 51 is mounted on the outer end of the stem 49 and cemented thereto, these parts being of plastic.

The disk 51 is concentric with the valve stem 20 and pushes valve 21 open against the action of spring 34 when the operator 5 is pushed inwardly. When the operator 5 is released, it is moved to its elevated position shown in Fig. 4, by the valve stem 20, valve 21 being urged to its closed position both by fluid pressure in the bag 25, when it has fluid contents as shown in Fig. 2, and by spring 34 whether the bag has fluid contents or not.

The valve 48 restricts the flow from the bag 25 to the outlet 2 by an increasing amount as the operator 5 is pushed inwardly and at the limit of its inward movement the valve 48 fits on the flat outer end 13 of the neck as shown in Fig. 3, to surround the port 23 and cut off the flow to the outlet 89, the check valve 21 being fully opened at this time. The ridge 33 may serve as a stop to limit the opening movement of valve 21 as shown in Fig. 3. The operator may, of course, be pushed in into an intermediate position to obtain a desired flow at the outlet 89.

The cartridge 6 is assembled in the casing bottom 3 by engaging the threads 30 of the cartridge with the internal threads 60 in the annular collar 61 of a cage 62, see Fig. 6, cage 62 is rotatably mounted in the casing bottom 3 and for this purpose the bottom 63 of the cage 62 has a spindle 64 which rotatably fits in a bore 65 in the base 66 of the casing bottom 3. The outer end of bore 65 is enlarged as shown at 67 to rotatably receive a washer 68 secured to the spindle 64 by a bolt 69. The bottom 63 of the cage extends outwardly beyond the inner end of bore 65 as indicated at 70 and is provided with a washer 71. The cage 62 has, depending from the collar 61, a cylindrical skirt 72 which is slightly smaller in diameter than the bore of the bottom 3 which has an elongated screw thread 73. The thread 73 is double lead and a multiple such as five times the pitch of the threads 4 and is reverse with respect to threads 4.

The collar 61 has peripheral spaced grooves as indicated at 75, six such grooves being shown, and the casing top 2 has cast integral therewith a corresponding set of six internal ribs indicated at 76 in Fig. 7, fitting the grooves 75, to rotate the cage 62 with its plunger 31 and the cartridge 6 with its bag 25 as a unit as the casing top 2 is rotated. The bottom 63 of the cage 62 has an inwardly extending boss 77 to center one end of a coiled compression spring 78 which bears at its other end against the plunger 31. As shown in Fig. 2, plunger 31 is inverted cup-shaped and the spring 78 bears against the flat bottom 79 of the plunger and the latter bears against the flat bottom 32 of the bag. The rim 81 of the plunger has four outwardly extending lugs such as indicated 82, these lugs 82 each riding in one of the four slots indicated at 83 equally spaced around and extending lengthwise of the sleeve 72. These slots 83 are each open at their lower end as indicated at 84 so as to permit the four lugs like 85 to pass upwardly of the sleeve 72 to a position where the lugs 82 on the plunger can be passed underneath them, by passing the plunger 31 into the open end 88 of

the sleeve, when these parts are assembled. Each of the four lugs 85 slide in one of the slots 83, and these lugs are on a retainer ring 86 having external screw threads 97 which mesh with the thread 73. The upper position of the plunger 31 is therefore determined by the position of the ring 86, unless that position is determined by the amount of fluid contents in the bag 25.

Assuming that the casing top 2 is removed, with no cartridge in place, a cartridge is inserted by engaging the threads like 30, see Fig. 5, on the cartridge with the threads 60, see Fig. 6, on the collar 61 of the plunger cage 62. During this time of handling the cartridge 6, if pressure is applied to the bag 25 by hand, the contents do not leak out as such pressure and spring 16 keep the check valve 21 closed. Then the top 2 is placed on the bottom 3 and it is oriented so that the ribs 76 on the top 2 will engage in the slots like 75 on the cage 62. Such engagement, as the top 2 is rotated, causes the ring 86 to advance in the opposite direction, namely, upwardly, at five times the speed, in the example given, from its lowermost position on threads 73 to its uppermost position shown in Fig. 2. Between ring 86 and the underside of collar 61 is arranged a gasket 87 to insure that ring 86 at its uppermost position will remain in threaded engagement with threads 73. With ring 86 at its uppermost position, it no longer restrains the upward movement of the plunger 31 under action of spring 78, the upward movement of plunger 31 proceeding until the fluid contents in the bag 25 are compressed by an amount determined by the strength of the spring 78, to thereby put the fluid contents in bag 25 under pressure so that such contents will be ejected from outlet 89 when the valve operator 5 is pushed inwardly. The reverse action takes place when the casing top 2 is unscrewed, namely, its rotation causes top 2 to move outwardly relatively to the casing bottom 3 while the rotation of cage 62 due to engagement of rib 76 with slots 75 causes ring 86 to move in the opposite direction, a distance five times as great as the length of screw threads 4, whereby lugs 85 engage lugs 82 and hold the plunger 31 adjacent the base 66, with spring 78 compressed, whereby the pressure of spring 78 does not have to be overcome when a fresh cartridge is inserted.

Behind valve 48 is a cushion chamber 92 at the inlet end of outlet 89, Fig. 3. The face cream passes into chamber 92 from the cartridge during downward movement of operator 5 while both valves 21, 48 are open. The purpose of this is to make the face cream in chamber 92 serve as a cushion to delay the closing of valve 21 and prolong discharge from outlet 89 when operator 5 is released, as otherwise very little face cream would be expelled if valve 21 both opened and closed quickly.

60 The thread 73 is relieved at its upper end as shown at 93 so that ring 86 will run off the upper end of thread 73 when the casing top 2 is screwed in place on bottom 3. At this time, elastic gasket 87 is compressed as shown in Figs. 2 and 4 to press the thread leads 97 on ring 86 in contact with the thread leads at the upper end of threads 73. This prevents stripping threads 73, 97 if ring 86 were to reach its uppermost position before the casing parts 2, 3 were screwed together. This mischance might be due

to surreptitious manual rotation of ring 86 before its proper rotation by coupling the casing parts together.

5 For a similar reason, the lower end of thread 73 is relieved as shown at 94, whereby, if ring 86 reaches its lowermost position before the casing parts are uncoupled, ring 86 freely rotates off the thread 73 but in end to end engagement therewith, ready to lift ring 86 at the proper time. 10 Preferably the casing thread 4 is 10% greater in effective length than thread 73, to insure that ring 86 will reach the limit of both its upward and downward stroke adjacent the relieved portions 93, 94.

15 While Fig. 2 illustrates the condition for the spring 78, unrestrained by lugs 85, acting on a full cartridge, if ring 86 were imagined lowered until its lugs 85 engaged 82, this figure would also substantially show the lowermost position 20 of the plunger 31 with the casing top 2 removed, although the lowermost position of plunger may be slightly lower than that illustrated and in that position the bottom 32 of the bag may either be free from or lightly rest on the end 79 of the plunger.

25 When the top 2 is screwed on to or unscrewed from the bottom 3, relative rotation between the bottom 79 of the plunger and the flexible bag 25 is prevented, as these parts rotate together and 30 with the plunger cage 62.

Various modifications may be made in the invention without departing from the spirit of the following claims.

I claim:

35 1. A dispenser comprising a casing having an outlet, a removable cartridge for said casing, an inwardly opening valve in said cartridge, a valve operator in said casing for said valve, and a second and inwardly closing valve on said operator, said cartridge having a port controlled by both of said valves, said outlet communicating with both of said valves.

40 2. A dispenser according to claim 1, said second valve being cup-shaped and seating on said cartridge, said casing having a cushion chamber behind said second valve in communication with said outlet.

45 3. A dispenser comprising a casing, a cartridge fitting in said casing, an inwardly opening reciprocating valve on said cartridge and a valve operator therefor on said casing, a bearing supporting said valve operator for rotary and reciprocating movement, said casing and said valve operator having cooperating lug and recess means preventing said valve operator from operating said valve when said valve operator is in one rotary position while permitting said valve operator to operate said valve when in another rotary position.

60 ROBERT GORDON BAU.
